United States Patent Office

Des. 188,340
Patented July 5, 1960

188,340

LINK FOR AN EXPANSIBLE BRACELET OR SIMILAR ARTICLE

Nathan Goodman, Forest Hills, N.Y., assignor to Baldwin Bracelet Corporation, New York, N.Y., a corporation of New York

Filed Aug. 27, 1959, Ser. No. 57,334

Term of patent 7 years

(Cl. D45—4)

Figs. 1 and 2 are respectively a top plan view and a side elevational view of a link embodying my new design;
Fig. 3 is a sectional view taken on line 3—3 of Fig. 1; and

Fig. 4 is a perspective view of one of the links.

I claim:

The ornamental design for a link for an expandable bracelet or similar article, substantially as shown.
